MASSAGE ROLLER

Imre Gaspar, 1156 N. Poinsettia Drive,
Los Angeles 46, Calif.

Filed July 28, 1964, Ser. No. 31,042

Term of patent 7 years

(Cl. D83—1)

FIGURE 1 is a longitudinal front view of a massage roller showing my new design;

FIGURE 2 is an end view of the massage roller shown in FIGURE 1; and

FIGURE 3 is an enlarged fragmentary transverse sectional detail of the massage roller of FIGURES 1 and 2, showing a pair of adjacent fluted peripheral portions of the roller.

I claim:

The ornamental design for a massage roller, substantially as shown.
